UNITED STATES PATENT OFFICE.

FRANKLIN P. MCCOIG, OF DURANT, OKLAHOMA.

CORN-POPPING MACHINE.

1,021,322.

Specification of Letters Patent. Patented Mar. 26, 1912.

Application filed March 2, 1911. Serial No. 611,775.

To all whom it may concern:

Be it known that I, FRANKLIN P. McCoig, a citizen of the United States, residing at Durant, in the county of Bryan and 5 State of Oklahoma, have invented certain new and useful Improvements in Corn-Popping Machines, of which the following is a specification.

This invention relates to corn popping 10 machines.

The object of the invention is to provide a casing having a discharge hopper at its lower end and a motor box at its upper end through which a feeding sleeve extends, the 15 latter having a feeding hopper at its upper end.

Another feature resides in the provision of a vertical screw conveyer extending through the sleeve and supporting a pan at 20 its lower end, the sleeve having radial fingers extending over the bottom of the pan.

Other objects are the provision of a connection with the conveyer in the motor box whereby power may be applied to the 25 conveyer from a suitable motor arranged in the box; and the provision of a sack support below the discharge hopper.

A still further object of the invention is to provide a machine of the character described that will be strong, durable, efficient and simple and comparatively inexpensive to construct, also one in which the several parts will not be likely to get out of working order.

With the above and other objects in view, 35 the invention has relation to certain novel features of construction and operation, an example of which is described in the following specification and illustrated in the accompanying drawings, wherein:

Figure 1 is a vertical sectional view of the machine, Fig. 2 is a partial plan view, Fig. 3 is a horizontal cross-sectional view taken on the line S—S of Fig. 1, Fig. 4 is a 45 horizontal cross-sectional view taken on the line X—X of Fig. 1, and Fig. 5 is a detail in elevation of the feeding sleeve.

In the drawings the numeral 1 designates a rectangular casing having glass sides 2, 50 one of which may be suitably arranged as a door whereby access may be had to the interior of the casing. The casing has at its lower end a discharge hopper 3 terminating in a spout 4. Supporting legs 5 extend 55 downward from the hopper 3. A headed rod 7 depends from the hopper adjacent the

spout and supports some distance below the spout, a plate or shelf 6 which is pivoted on the lower end of the rod and projects horizontally under the spout. This shelf is used 60 to support a paper sack under the spout which is filled as the corn is popped.

Over the upper end of the casing a motor box or chamber 8 is provided. In the top central portion of the box a feed hopper 9 65 is mounted. This hopper has a collar 10 extending a short distance into the box. A feeding sleeve 11 extends through the bottom of the box and down into the casing, the sleeve having at its upper end a shoulered flange 12. A collar 14 has its lower end bearing in the flange and at its upper end surrounds the collar 10. A gear member 15 is fixed about the collar 14 and is adapted to have driven connection with a 70 suitable motor, as a spring, electric or weight motor. It is to be understood that a pulley (not shown) may be substituted for the gear member.

Within the sleeve 11 a vertical conveyer 80 shaft 16 is suspended. This shaft projects a short distance below the sleeve and extends up into the hopper 9. Opposite the collar 14 the shaft is fixed thereto by a transverse bar 17 and thus when the collar 85 is rotated motion is imparted to the shaft.

A short conveyer screw or section 18 is secured to the shaft immediately above the bar 17. This conveyer section extends into the feed hopper and when in motion carries 90 the corn which has been placed in said hopper, down to the sleeve. In the sleeve another conveyer screw or section 19 is mounted on the shaft and extends from the bar 17 to the lower end of the sleeve. On the lower 95 end of the shaft an annular pan 20 is secured. This pan is somewhat larger in diameter than the sleeve and surrounds the same. The bottom of the pan is held in close proximity to the end of the sleeve

which has a plurality of notches 21 through which the corn brought down by the conveyer escapes into the pan. A plurality of fingers 22 radiate from the lower end of the sleeve and extend over the bottom of the pan, terminating near the annular retaining wall of the pan.

The pan being fixed on the shaft 16 is rotated therewith, while the fingers being fixed on the sleeve remain stationary. Under the pan a suitable burner 23 is supported by its supply pipe 24 which leads into 105 110

the casing from a tank 25 supported at one side of the latter. The heat from the burner causes the corn in the pan to "pop" and the fingers agitate the corn as the pan is rotated. 5 As the corn "pops" it is thrown out of the pan and falls into the discharge hopper 3 from which it is delivered to the sack by the spout 4.

For holding the pan 20 against lateral 10 displacement a bearing ring 26 is mounted on the sleeve and suitably secured thereto. A collar 27 freely fitting about the sleeve is rotatable on the collar. From this collar arms 28 extend downward and outward and 15 have their lower ends secured to the retaining wall of the pan.

It is obvious that corn fed into the hopper will be carried down into the machine, "popped" and deposited in the sacks with- 20 out attention from the operator and pop corn produced in quantities in an expeditious and efficient manner.

What I claim, is:

1. In a corn popping machine, a vertical 25 casing, a discharge hopper at the lower end of the casing, a motor box mounted on the casing, a feeding sleeve in the casing, a conveyer in the sleeve, a rotatable pan connected with the conveyer and surrounding 30 the sleeve into which the latter discharges, an agitator carried by the sleeve and extending into the pan, a gear member connected to the conveyer within the motor box, a feed hopper supported over the sleeve, and a 35 burner located under the pan.

2. In a corn popping machine, a vertical casing, a feeding sleeve depending into the casing, a conveyer mounted in the sleeve, a rotatable pan at the lower end of the 40 sleeve into which the latter discharges, an agitator carried by the sleeve and extending into the pan, a gear member connected with the conveyer, a burner located under the pan, and a feed hopper over the sleeve.

45 3. In a corn popping machine, a vertical casing, a rotatable pan mounted in the casing, a sleeve depending in the casing and having its lower end adjacent the pan, said sleeve having provision for discharging into 50 the pan, fingers radiating from the sleeve and extending over the pan, a conveyer mounted in the sleeve, a burner located under the pan, and a feed hopper mounted over the sleeve.

55 4. In a corn popping machine, a vertical casing, a discharge hopper at the bottom of the casing, a spout attached to the hopper, a sack support under the spout, a motor box

mounted on the casing, a sleeve depending from the motor box into the casing and having a discharge opening at its lower end, a rotatable pan mounted below the sleeve, an agitating device carried by the sleeve and operating in the pan, a conveyer suspended in the sleeve, a gear member in the motor box having connection with the conveyer, a burner located under the pan, and a hopper over the sleeve. 60

5. In a corn popping machine, a vertical casing, a feeding sleeve depending into the 70 casing, a conveyer mounted in the sleeve, a gear member connected with the conveyer, a rotatable pan below the sleeve connected with the conveyer, said sleeve having discharge openings within the pan, an agitating device connected to the sleeve and projecting into the pan, a bearing member connected to the pan and surrounding the sleeve, a burner adjacent the pan, and a feed hopper supported over the sleeve. 75

6. The combination in a corn popping machine, of a vertical casing, a sleeve fixed in the vertical casing against rotation, a screw conveyer mounted to revolve in the sleeve, a rotatable pan supported under the 85 sleeve, said sleeve being in position to discharge into the pan, an agitator extending from the sleeve into the pan, a gear member having connection with the conveyer, a burner adjacent the pan, and a feed hopper 90 over the sleeve.

7. In a corn popping machine, a vertical casing, a discharge hopper at the bottom of the casing, a motor box mounted on the casing, a vertical sleeve depending from the 95 motor box into the casing and having a discharge opening at its lower end, a screw conveyer suspended in the sleeve, a rotatable pan below the sleeve having connection with the conveyer, an agitator carried by the 100 sleeve and extending into the pan, a burner under the pan, a feed hopper supported on the motor box over the sleeve, a rotatable collar between the feed hopper and the sleeve, said collar being located in the motor box, a rigid connection between the conveyer and the collar, and a gear member attached to the collar. 105

In testimony whereof I have signed my name to this specification in the presence of 110 two subscribing witnesses.

FRANKLIN P. McCOIG.
